Attorney.

UNITED STATES PATENT OFFICE

2,287,688

HEDDLE FRAME

John Jacob Kaufmann, Elkins Park, Pa., assignor
to Steel Heddle Manufacturing Company, Phil-
adelphie, Pa., a corporation of Pennsylvania

Application May 8, 1941, Serial No. 392,435

8 Claims. (Cl. 139—92)

This invention relates to heddle frames for looms, and it relates more particularly to certain improvements in the devices for supporting, intermediate their ends, the heddle bars which are employed in heddle frames of the type at present most commonly used.

Heretofore, one of the principal difficulties encountered in the use of heddle frames in which the top and bottom rails are made of wood, and in which devices, known in the industry as "hooks," are mounted for supporting the heddle bars intermediate their ends, has been that the wooden rails would become distorted and thereby disturb the alinement and parallelism of the heddle bars. It is, of course, well understood that the heddle bars must be maintained in the proper spaced and parallel relationship, as otherwise the heddles will bind on the bars and imperfections in the weave will result.

One of the principal faults, in connection with the devices for supporting the heddle bars in the frames, has been that no entirely satisfactory means has heretofore been devised for mounting the heddle bar supporting devices in the wooden rails in such manner that the same may not only be readily and conveniently adjusted therein, but will be firmly held in their adjusted positions.

The principal object, therefore, of the present invention is to provide, in connection with the devices for supporting the heddle bars intermediate their ends, improved means for mounting said devices in the top and bottom rails of the heddle frames, and for permitting the necessary adjustment thereof while, at the same time, serving to hold said devices in their adjusted positions to the end that the heddle bars may be held properly spaced and in their proper parallel relationship.

A further object of the invention is to provide, in connection with the devices for supporting the heddle bars intermediate their ends, improved means for mounting said devices in the top and bottom rails of the frames, which will be simple and efficient, and which may be inexpensively constructed.

A further object of the invention is to provide heddle bar supporting devices which may be readily adjusted in the rails in which they are mounted without requiring the use of special tools, or a high degree of skill on the part of the operator in making the required adjustments.

The nature and characteristic features of the invention will be more readily understood from the following description, taken in connection with the accompanying drawing forming part hereof, in which:

Figure 1 is an elevational view of a heddle frame provided with heddle bar supporting devices having improved means for securing the same in the top and bottom rails of the heddle frames, said 5 means embodying the main features of the present invention;

Fig. 2 is an enlarged detail view, illustrating more clearly the construction and arrangement of the parts, certain of the parts being shown in 10 section;

Fig. 3 is a transverse section taken approximately on the line 3—3 of Fig. 2;

Fig. 4 is a perspective view of one of the elements of the present invention detached; and

Fig. 5 is a similar view of another of said elements.

It will, of course, be understood that the description and drawing herein are illustrative merely, and that various modifications and 20 changes may be made in the structure disclosed without departing from the spirit of the invention.

Referring to the drawing, the heddle frame there shown comprises top and bottom rails 10, usually made of wood and connected at their end portions by metallic end struts 11. The heddle bars 12 are mounted in the frame, in the customary manner, with their respective end portions supported in the end struts 11 and secured 30 therein, in the usual manner, by spring members 13. The heddles 14, which may be of any preferred type, are also mounted on the heddle bars 12 in the customary manner.

The inner end portion of the supporting device, 35 which engages each of the heddle bars 12, may be of any preferred construction, such for example, as that shown in my previous Letters Patent, No. 1,821,647, comprising a bolt member 15 having its inner end portion flattened as at 40 16 and provided with side plates 17 secured thereto. The side plates 17 are recessed as at 18 for the reception and support of the heddle bars 12. There is also provided a slide member 19, having leg portions guided between the side plates and 45 provided with overlapping lips 20 which serve to confine the heddle bars 12 in the recesses 18. The slide member 19 is impelled to the locking position by means of a coil spring 21 which surrounds the bolt member 15. The coil spring 21 bears at one end against a portion of the slide member 19, and at its other end against lugs 22 struck up from the shank of the bolt member 15.

The bolt member 15 extends entirely through the rail 10 with a snug fit, and the outer end 50 thereof is suitably threaded as at 23 over a sub-

stantial portion of its length. The threaded end 23 of the bolt member 15 engages the complementally threaded aperture 24 of a block member 25 which is mounted on the outer edge of the rail 10, being positioned thereon by means of the wood screws 26, which pass through apertures 27 provided in the end portion of the block member 25. The wood screws 26 are threaded into the rail 10.

There is also provided, in conjunction with the block member 25, a deformable plate member 28, which likewise has a central aperture 29 threaded complementally to the threaded end of the bolt member 15, which it engages at a slight distance from the outer face of the block member 25. The plate member 28 is also provided in its end portions with apertures 30 which register with the apertures 27 in the block member 25, and through which the wood screws 26 also extend. The heads of the wood screws engage the outer face of the deformable plate member 28 so that when the wood screws 26 are tightened, the end portions of the plate member 28 will be brought into contact with the block member 25, thereby serving to grip the threads 23 of the bolt member and thus prevent undesirable turning of the bolt member 15, and the supporting device carried thereby.

When it is desired to adjust the heddle bar supporting device in the frame, the heddle bars are first removed from said supporting device by first manually moving the slide member against the tension of the coil spring 21. The bars may then be withdrawn from the recesses in the plates in which they are normally positioned. The wood screws 26 are then loosened, by means of an ordinary screw driver, a sufficient distance to allow a certain freedom of movement of the plate member 28 in a direction corresponding to the axis of the bolt member 15, whereupon said bolt member may be freely rotated to bring the recesses 18 in the plate members 17 to the proper distance from the rail 10. The adjustment having been made, it is then merely necessary to again tighten the wood screws 26 to cause the plate members 28 to grip the threads 23 of the bolt member 15. The supporting device will then be fixedly and securely held and will not become loosened or disarranged by reason of the shocks and jars to which the structure is subjected in the shedding operation of the loom.

I claim:

1. A supporting device for the heddle bars of loom harness frames including a bolt member, means carried by said bolt member for supporting a heddle bar, said bolt member having a threaded portion, a block member mounted on the rail of the frame and having a threaded aperture engaged by the threaded portion of the bolt member, a plate member positioned a short distance from the block member and having a threaded aperture engaged by the threaded portion of the bolt member, and means for pressing the plate member toward the block member to cause the plate member to grip the threads of the bolt member.

2. A supporting device for the heddle bars of loom harness frames including a bolt member, means carried by said bolt member for supporting a heddle bar, said bolt member having a threaded portion, a block member mounted on the rail of the frame and having a threaded aperture engaged by the threaded portion of the

5 bolt member, a plate member positioned a short distance from the block member and having a threaded aperture engaged by the threaded portion of the bolt member, and means mounted in the rail engaging the end portions of the plate member and block member to cause the plate member to grip the threads of the bolt member.

10 3. A supporting device for the heddle bars of loom harness frames including a bolt member, means carried by said bolt member for supporting a heddle bar, said bolt member having a threaded portion, a block member mounted on the rail of the frame and having a threaded aperture engaged by the threaded portion of the bolt member, a deformable plate member positioned a short distance from the block member and having a threaded aperture engaged by the threaded portion of the bolt member, and means mounted in the rail engaging the end portions 15 of the plate member and block member to cause the plate member to grip the threads of the bolt member.

20 4. A supporting device for the heddle bars of loom harness frames including a bolt member, means carried by said bolt member for supporting a heddle bar, said bolt member having a threaded portion, a block member mounted on the rail of the frame and having a threaded aperture engaged by the threaded portion of the bolt member, a plate member positioned a short distance from the block member and having a threaded aperture engaged by the threaded portion of the bolt member, and screws mounted in the rail and passing through apertures in the 25 plate member thereby to cause the plate member to grip the threads of the bolt member when said screws are tightened.

30 5. A supporting device for the heddle bars of loom harness frames including a bolt member, means carried by said bolt member for supporting a heddle bar, said bolt member having a threaded portion, a block member mounted on the rail of the frame and having a threaded aperture engaged by the threaded portion of the bolt member, a deformable plate member positioned a short distance from the block member and having a threaded aperture engaged by the threaded portion of the bolt member, and screws mounted in the rail and passing through apertures in the 35 plate member thereby to cause the plate member to grip the threads of the bolt member when said screws are tightened.

40 6. A supporting device for the heddle bars of loom harness frames including a bolt member, means carried by said bolt member for supporting a heddle bar, said bolt member having a threaded portion, a block member mounted on the rail of the frame and having a threaded aperture engaged by the threaded portion of the bolt member, a plate member positioned a short distance from the block member and having a threaded aperture engaged by the threaded portion of the bolt member, and screws mounted in the rail and passing through apertures in the plate member thereby to cause the plate member to grip the threads of the bolt member when said screws are tightened.

45 7. A supporting device for the heddle bars of loom harness frames including a bolt member, means carried by said bolt member for supporting a heddle bar, said bolt member having a threaded portion, a block member mounted on the rail of the frame and having a threaded aperture engaged by the threaded portion of the bolt member, a plate member positioned a short distance from the block member and having a threaded aperture engaged by the threaded portion of the bolt member, and screws mounted in the rail and passing through registered apertures in the plate member and block member thereby to cause the plate member to grip the threads of the bolt member when said screws are tightened.

50 70 75 8. A supporting device for the heddle bars of loom harness frames including a bolt member, means carried by said bolt member for supporting a heddle bar, said bolt member having a threaded portion, a block member mounted on the rail of the frame and having a threaded aperture engaged by the threaded portion of the

bolt member, a deformable plate member positioned a short distance from the block member and having a threaded aperture engaged by the threaded portion of the bolt member, and screws mounted in the rail and passing through registered apertures in the plate member and block member thereby to cause the plate member to grip the threads of the bolt member when screws are tightened.

8. A supporting device for the heddle bars of loom harness frames including a bolt member, means carried by said bolt member for supporting a heddle bar, said bolt member having a

threaded portion, a block member mounted on the rail of the frame and having a threaded aperture engaged by the threaded portion of the bolt member, a deformable plate member 5 positioned a short distance from the block member and having a threaded aperture engaged by the threaded portion of the bolt member, and wood screws threaded in the rail and passing through registered apertures in the plate member and block member thereby to cause the plate member to grip the threads of the bolt member when said screws are tightened.

JOHN JACOB KAUFMANN.
